CLAIM

The ornamental design for a female urinary catheter, as shown and described.

DESCRIPTION

FIG. 1 is an isometric view of a design for a female urinary catheter showing environment of a container attached to a female urinary catheter;

FIG. 2 is an isometric view of a design for a female urinary catheter;

FIG. 3 is a front side view thereof;

FIG. 4 is a back side view thereof;

FIG. 5 a top side view thereof, where a bottom side view is not shown as it is a mirror image to the top side view;

FIG. 6 is a left side view of FIG. 2 and a right side view of FIG. 1;

FIG. 7 is a right side view of FIG. 2; and,

FIG. 8 is a view of an enlarged portion of a handle of the female urinary catheter shown in FIG. 2.

In FIG. 1 the broken lines of the container environment and the broken lines on an end of the female urinary catheter form no part of the claimed design.

In FIG. 6 the broken lines form no part of the claimed design.

The dot-dash broken lines represent boundaries of the enlarged portion and forms no part of the claimed design.
